SUBCALIBER PROJECTILE

Charles L. Critchfield, Chevy Chase, Md., assignor
to the United States of America as represented
by the Secretary of the Navy

Application January 18, 1944, Serial No. 518,753

1 Claim. (Cl. 102—93)

1

This invention relates to projectiles for guns and more particularly to sub-caliber projectiles adapted to attain high velocities when fired from a gun.

One object of my invention is the provision of a projectile for guns, which includes a sub-caliber core and a detachable sabot. The projectile is light in weight as compared with ordinary standard projectiles and presents a substantially full caliber rear surface to pressures developed in the gun barrel, the new projectile being capable of attaining a higher velocity in the barrel and maintaining that velocity throughout reasonable distances of flight with maximum stability.

Another object of my invention is to provide a sub-caliber projectile having a sabot which is readily discarded during flight with minimum tendency of the core to yaw or deviate from the accurate course of travel, and without decreasing the velocity of the projectile.

Another object of my invention is to provide a projectile having a sub-caliber core and having distendable centering means to ensure a snug well centered fit of the projectile during its travel through the gun bore.

A further object of my invention is to provide a projectile as described above which is simple to manufacture and is adapted to large quantity production.

These and other objects of the invention will be apparent from the following specification and the accompanying drawing, in which

Fig. 1 is a side elevation of a preferred form of projectile made in accordance with my invention; Fig. 2 is a longitudinal cross-sectional view taken on line 2—2 of Fig. 1; and Fig. 3 is a front elevation of the projectile.

As conducive to a clearer understanding of certain features of my invention, it may be noted at this point that projectiles including sub-caliber cores and sabots for making the cores suitable for full caliber use have a number of advantages which ordinary standard projectiles do not possess. Projectiles having sub-caliber cores are lighter in weight than standard projectiles of equivalent caliber and may be fired from rifled, standard guns so as to take full effect of pressures developed in the gun. The projectiles leave the gun at very high muzzle velocity and have potentially high striking power. Where the sabot releases from the projectile core during flight, the negative accelerating effect of the atmosphere is considerably reduced and higher striking velocities are made possible.

2

Despite the many recognized advantages of projectiles having sub-caliber cores, the projectiles are not widely used; one reason being that heretofore they have not been reliably stable in flight before the release of the sabot. One cause of this is due to poor axial centering of the projectiles as they move through the gun tube, causing the projectiles to tend to overturn or deviate in flight after leaving the gun.

5 A variety of materials and designs have been proposed in sabot-construction involving especially the use of reinforced plastics, aluminum alloys and tubular steel. In these constructions the sub-caliber projectile is centered in the sabot which in turn is to be centered in the bore of the gun, and this composite structure thus requires more care in attaining a properly centered projectile. In addition to the disadvantage of a larger number of critical tolerances, previous 10 sabots compared less favorably with standard ammunition because the sabot often yielded farther under transverse stresses than a steel projectile, and because the sabot was usually, though not necessarily, shorter than standard ammunition. The less certain centering of the sabot projectile combined with its inherently lower stability caused it to show larger yaw and dispersion than full caliber projectiles in the same gun.

15 Another difficulty encountered is that of obtaining release of the sabot soon after the projectile leaves the gun muzzle. In this connection, some of the heretofore known sabots have failed to release with the result that the entire purpose of the projectile is defeated. In other cases, certain sabots in releasing upset the equilibrium of the core.

20 A projectile made in accordance with the present invention has a sub-caliber core and substantially full caliber sabot means making the core suitable for firing from a rifled gun at high velocities. The projectile is well centered during travel through the gun barrel as well as stable in flight up to and after the time of discard of the sabot, which takes place promptly upon the projectile's leaving the gun bore in order to minimize the retarding effect of the atmosphere without upsetting stability of the core.

25 Referring now more particularly to the practice of my invention, I find that a projectile assembly having a sub-caliber core and substantially full caliber discardable sabot means is effectively stabilized in a rifled gun and in flight, through the inclusion of distendable centering 30 means as a part of the projectile for insuring

snug, well-centered fit of the projectile during travel through the gun barrel. In this connection, I prefer to employ a distendable ring or rings, made for example of plastic material, mounted about the main body of the projectile, preferably around a reduced diameter section of the sabot, and adapted to expand to a position of snug contact with the lands of the gun. The sabot means employed is released by air pressure and centrifugal force shortly after leaving the gun.

In the drawing, the projectile includes an elongated, cylindrical sabot 10 having an axial bore 11 into which a sub-caliber core 12 snugly fits, as by force fit or by threading. The sabot includes an elongated, axially-bored cylindrical sleeve or skirt 13 of substantially full caliber diameter disposed tightly around the side walls of the core, leaving the ogive portion 12a of the core protruding therefrom in a forward direction. The skirt 13 is made of light material, for example, plastic having a laminated fibrous filler, and preferably includes zones of weakness, such as symmetrically spaced radial cuts 14 extending from the forward edge well to the rear of the skirt body for insuring ready release of the entire sabot by centrifugal force during flight of the projectile. The sabot preferably includes at the rear of the skirt portion a substantially full caliber base plug 15 which is made, for example, of Duralumin and has a forwardly protruding portion 16 of reduced diameter secured, as by press fit or by threading, in the bore of the skirt 13. The base plug 15 carries a rotating band 17 made, for example, of copper.

A ring 18, preferably made of plastic, is seated around the forward end of sabot 10 to act as a slidable bourrelet. The inside surface of the bourrelet and the outer surface of the forward end portion of the skirt 13 form the surface of a cone having substantially the same axis as the skirt bore. The conical surface on the skirt terminates at its rear or enlarged end in a shoulder 19 which serves to stop sliding movement of the bourrelet during acceleration in the gun.

When the projectile is fired from a gun, the slidable bourrelet 18 moves back, influenced by setback due to axial acceleration of the projectile. The bourrelet expands on the conical surface of the skirt until the shoulder 19 of the skirt is engaged, thus compensating for radial clearance or compressibility of the sabot, and effecting positive centering of the projectile in the gun. Shortly after the projectile leaves the gun, the bourrelet 18 and sabot 10 are discarded under the action of centrifugal force; the bour-

relet breaking readily, and the zones of weakness or cuts 14 in the skirt 13 aiding in ready discard of the sabot, including the skirt and the base plug 15. The projectile core moves accurately, is quite stable in flight, and possesses high striking power throughout prolonged distances of travel.

It will be understood that my invention may be used to good advantage in connection with projectile cores and sabots of widely differing caliber. One type of projectile employed included an eleven millimeter core made of machinable alloy tungsten. A twenty millimeter sabot, having a plastic skirt, a Duralumin bore plug and a copper rotating band, was fitted snugly around the core. A slidable plastic bourrelet was disposed around the outer forward surface of the sabot. The projectile, when fired from a gun, exhibited excellent ballistic properties.

The projectile of my invention is simple to assemble and possesses highly favorable ballistic properties, including stability, rapidity of flight and high potential striking power.

Although I have described one embodiment of the invention, it is obvious that many possible modifications of the invention may be made, and it will be understood that the matter described and illustrated herein is to be interpreted as illustrative and not in a limiting sense.

I claim:

A projectile comprising a subcaliber core, a base plug backing the core and having a forwardly protruding portion the same in diameter as the core, a rotating band of channel cross-section fitted on the base plug, and a cylindrical sleeve disposed tightly on the core, overlapping the forwardly protruding portion and abutting one of the flanges of the rotating band.

CHARLES L. CRITCHFIELD.
